FOCUSING DEVICE FOR ATTACHMENT TO CAMERAS OR PROJECTORS

Felix L. Bednarz, Beverly Hills, Calif., assignor to
McCulloch Motors Corporation, Los Angeles, Calif., a
corporation of Wisconsin

Application July 2, 1954, Serial No. 31,257

Term of patent 7 years

(Cl. D61—1)

FIG. 1.

FIG. 2.

FIG. 3.

FIG. 4.

Fig. 1 is a perspective view of a focusing device for attachment to cameras or projectors showing my new design;

Fig. 2 is a side elevational view thereof.

Fig. 3 is a front end elevational view thereof; and

Fig. 4 is a rear end elevational view thereof.

I claim:

The ornamental design for a focusing device for attachment to cameras or projectors, as shown.
